EDWARD MORRIS NORTON, OF NEW YORK, N. Y., ASSIGNOR TO DE LA VERGNE
MACHINE COMPANY, OF NEW YORK, N. Y.

VAPORIZER ATTACHMENT.

1,079,950.

Specification of Letters Patent.

Patented Dec. 2, 1913.

Application filed February 6, 1913. Serial No. 746,581.

To all whom it may concern:

Be it known that I, EDWARD MORRIS NORTON, a citizen of the United States, residing in the borough of Manhattan, in the city, county, and State of New York, have invented certain new and useful Improvements in Vaporizer Attachments, of which the following is a full, clear, and exact description, reference being had to the accompanying drawings, forming a part of this specification.

This invention relates to improvements in the construction of vaporizers, such as used in connection with certain types of internal combustion engines, and its primary object is to provide a simple and efficient device whereby the formation of soot and carbon deposits in the vaporizing chamber will be prevented.

20 A further object of this invention is to provide a vaporizer cleaning device of a simple and novel construction which can be readily attached to the vaporizer of an engine without necessitating any change in the construction of the same.

With these and other objects in view as will more fully appear as the description proceeds, this invention consists of certain improved constructions and arrangements of parts as will be hereinafter described and claimed in the appended claims.

Internal combustion engines and particularly those types of oil engines provided with a vaporizer in which a charge of oil is injected and vaporized previous to its admission to the cylinder, are generally not entirely free from inconveniences, especially in regard to imperfect combustion and consequent formation of injurious deposits on the inside surface of the vaporizer, requiring the same to be cleaned at the end of each day of service. Such imperfections are also to be found in those engines where the mixture of oil and air is injected directly into the cylinder and to prevent the same, various schemes have been devised, generally based on the admission of water or steam together with the explosive mixture; these schemes have all met with more or less unsatisfactory results. The admission of a certain amount of water in the cylinder, for instance, is open to the objection that encrustations form on the valves and other parts; and furthermore, the putting in operation of these schemes usually necessi-

tates a special construction of the cylinder and other parts of the engine.

The present device is intended for use in those engines having a vaporizing chamber directly connected to the cylinder, and particularly in connection with engines of the Hornsby-Ackroyd type. In this engine the oil is injected inside of the vaporizer which is placed in front of the cylinder, and which connects therewith by means of a bottle-neck connection. Vaporizing is conducted in the interior of a combustion chamber, which is so arranged that the heat of the explosion maintains it at a temperature considerably high to enable the oil to be vaporized by mere injection upon the hot surface. On the suction stroke of the piston, air is taken into the cylinder through the air inlet valve without passing through the vaporizer chamber. In the meantime the oil which is thrown into the vaporizer is vaporizing and diffusing itself through the vaporizer chamber mixing with the hot products of combustion left by the preceding explosion. During this stroke therefore, the air enters through the cylinder and the vapor formed from the oil is almost entirely confined to the combustion chamber. On the return stroke of the piston air is forced through the bottle neck connection into the combustion chamber and is there mixed with the vapor contained in it. As the compression proceeds more and more air is forced into the vaporizer or combustion chamber, and just as compression is completed the mixture attains proper explosive proportions. The surface of the chamber is sufficiently hot to cause explosion, under the pressure of which the piston moves in its working stroke. As stated before, it is usually necessary to clean the vaporizer chamber of these engines at the end of each working day, on account of the deposit of soot or other unburned particles of combustion within the same. This is possibly formed in the period of relative rest of the products of combustion contained within the vaporizer chamber at the end of the working stroke of the piston and during the exhaust stroke; and therefore I have devised means whereby such burned particles are continually removed as they are formed, incidentally said means being at the same time helpful toward forming an explosive mixture which explodes more readily and which is more active in its effects.

The annexed drawings are intended to illustrate one of the ways of putting my invention into practice, and in the same Figure 1 is a detail view in elevation partly sectioned showing the vaporizer chamber of a Hornsby-Ackroyd engine with my device attached, and Fig. 2 is a rear elevation detail view in an enlarged scale, showing the preferred way of holding the cock controlling the flow of water through my device, at different graduations of opening.

Referring to said drawings, 10 is the vaporizer chamber communicating with the inside of the cylinder 11, by means of a bottle-neck connection 12; said vaporizer chamber is provided with water jacket 13, 14 representing the inlet to said water jacket. The vaporizer chamber is fitted with a cap 15, which is normally incandescent during the operation of the engine and against the inside surface of which the oil is injected. To start the engine said cap is heated by a separate heating lamp. I have found that by letting hot air or preferably steam or hot air imbued with moisture within the vaporizer chamber during the suction stroke of the piston, the deposits due to the previous explosion are efficiently removed from the surface of the vaporizer. To this end I provide a pipe 16 leading from the inside of a box 17 to the vaporizer chamber. Said box is provided with a suction pipe 18, having a flaring portion 19, which comes quite close to the surface of the vaporizer cap; said suction pipe is preferably pivotally mounted on the top of said box 17, as shown in 20, the object of this being the possibility of removing the same from its normal position close to the vaporizer cap when it is necessary to start the engine and therefore to heat said cap from the outside. Pipe 16 is provided with a stop-cock 21, and between said pipe 16 and the inside of box 17 is also provided a check valve 22, opening toward the vaporizer chamber. It is obvious that when stop cock 21 is open, the suction exerted by the piston during its suction stroke will cause an inflow of air between flaring portion 19, and the surface of vaporizer cap 15, through suction pipe 18, box 17 and pipe 16, to the inside of the vaporizer chamber; and moreover, said air being forced to pass close to the surface of vaporizer cap 15, which is incandescent, will be heated. During the exhaust and the compression strokes of the piston, check valve 22 will remain closed and therefore no gases or products of combustion will come out of the vaporizer chamber. To further increase the efficiency of my device, I provide means whereby said heated air takes up steam or moisture during its course, conveying the same to the vaporizer chamber; and to this end I provide a pipe 23 with a tank or receptacle 24; said connection can be opened

or closed by means of a stop cock 25. Said tank or receptacle 24 is provided with filtering means for the water coming from the water jacket, these consisting for instance, of partitions of fine wire gauze 26, inserted between the lower and the upper part of said tank or receptacle; these will prevent the entrance of slight particles, which may be contained in the water, to box 17 and from there to the inside of the vaporizer chamber. At the upper part of said tank or receptacle, I provide a faucet 27 leading to a funnel like portion 28, provided on the top of box 17; the flow of water from said faucet can be controlled by a cock 29, which can be secured at different degrees of opening; this can be effected in any desired manner, a simple way being that illustrated in Fig. 2, from which it is seen that the elongated handle 30 of said cock can be retained by its own elasticity in one of the indentations provided in a rack 31.

32 designates a partition between the upper and lower portion of box 17, said partition consisting preferably of fine metallic wire gauze.

The flow of water through faucet 27 is due to gravity, the difference in level between the upper part of the water jacket and said faucet being quite sufficient for this purpose. Said water gradually falls on wire gauze 32, which is heated by the hot air coming from suction pipe 18, and spreading on the surface of said wire gauze, is taken up by said hot air partly in the form of moisture, the mist thus formed reaching the vaporizer chamber in the best condition for removing the deposits on the surface thereof.

I have found this device to be extremely efficient, so much so that the cleaning of the vaporizer at the end of each working day is no longer needed, it being sufficient to clean the same once every two or three months.

It is obvious that in order to carry my invention into practice, it is not necessary to closely follow the details of the structure illustrated and described. The same are susceptible of being modified to a considerable extent, without any radical departure being made from the fundamental idea of my invention; therefore I reserve myself the right of bringing to my invention all those changes and modifications which may be deemed useful or necessary to comply with the requirements of different cases, and which may enter fairly into the scope of the appended claims.

I claim:

1. In an explosion engine the combination of a cylinder, a vaporizer chamber directly opening therein, a water jacket for said chamber, a box, a metallic perforated partition within said box, means for dripping

water coming from said water jacket on said partition, a suction tube leading hot air from points close to the outside surface of said vaporizer chamber to the inside of said box, 5 and a connection leading said air and moisture from said box through said partition to the inside of said vaporizer chamber.

2. In an explosion engine the combination of a cylinder, a vaporizer chamber directly opening therein, a water jacket for said chamber, a piston, a box connected to the inside of said vaporizer chamber, a valve between said box and said chamber opening during the suction stroke of said piston, a metallic perforated partition within said box, means for dripping water coming from said water jacket on top of said partition, and a suction tube leading hot air from points close to the outside surface of said vaporizer chamber to said box on the same side of said partition, said tube being mounted on a swivel so as to be movable to and from its normal position.

3. In an explosion engine, the combination of a cylinder, a vaporizer chamber directly opening therein, a water jacket for said chamber, a piston, a box connected to the inside of said vaporizer chamber, a valve between said box and said chamber opening during the suction stroke of said piston, a metallic perforated partition within said box, means for dripping water coming from said water jacket on top of said partition, a suction tube leading hot air from points close to the outside surface of said vaporizer chamber to said box on the same side of said partition, said tube being mounted on a swivel so as to be movable to and from its normal position, and means for filtering said water previous to its being delivered to the inside of the vaporizer chamber.

4. In an explosion engine the combina-

tion of a cylinder, a vaporizer chamber directly opening therein, a water jacket for 45 said chamber, a piston, a box connected to the inside of said vaporizer chamber; a valve between said box and said chamber opening during the suction stroke of said piston, a metallic perforated partition within said 50 box, means for dripping water coming from said water jacket on top of said partition, a suction tube leading hot air from points close to the outside surface of said vaporizer chamber to said box on the same side of 55 said partition, said tube being mounted on a swivel so as to be movable to and from its normal position, means for filtering said water previous to its being delivered to the inside of the vaporizer chamber, and means 60 for regulating the flow of the same.

5. In an explosion engine the combination of a cylinder, a vaporizer chamber directly opening therein, a water jacket for said chamber, a piston, a box connected to the inside of said vaporizer chamber, a valve between said box and said chamber opening during the suction stroke of said piston, a metallic perforated partition within said box, means for dripping water coming from 70 said water jacket on top of said partition, a suction tube leading hot air from points close to the outside surface of said vaporizer chamber to said box on the same side of said partition, said tube being mounted on a swivel so as to be movable to and from its normal position, means for filtering said water previous to its being delivered to the inside of said box, means for regulating the flow of the same, and means for closing the 75 80 connection between said box and said vaporizer chamber.
